UNITED STATES PATENT OFFICE.

PAUL W. LAMSON, OF CLEVELAND, OHIO, ASSIGNOR TO ARMSTRONG CORK COMPANY, OF PITTSBURGH, PENNSYLVANIA, A CORPORATION OF PENNSYLVANIA.

STEAM-PIPE INSULATION AND SUPPORT.

1,122,130.

Specification of Letters Patent. Patented Dec. 22, 1914.

Application filed September 11, 1913. Serial No. 789,388.

To all whom it may concern:

Be it known that I, PAUL W. LAMSON, a citizen of the United States, residing at Cleveland, in the county of Cuyahoga and State of Ohio, have invented a new and useful Improvement in Steam-Pipe Insulation and Supports, of which the following is a full, clear, and exact description, reference being had to the accompanying drawings, forming part of this specification, in which—

Figure 1 is a side elevation partially in section of a conduit containing a steam or other pipe supported therein. Fig. 2 is a vertical transverse section on the line II—II of Fig. 1. Fig. 3 is an end view of the steam pipe support; and Fig. 4 is a side elevation thereof.

This invention relates to an improvement in insulated pipe supports which are incased in terra cotta pipes and are also incased in insulating material.

The invention is more particularly directed to the support for the pipe and is arranged to normally maintain the pipe in a central position within the terra cotta pipes, and at the same time permit the conveyer pipe to expand and contract.

A further object of my invention is to provide a support in which the conveyer pipe will be supported at suitable intervals on pedestals through the medium of the terra cotta pipes.

The precise nature of my invention will be best understood by reference to the accompanying drawings, which will now be described, it being premised, however, that changes may be made in the details of construction and the general arrangement of the parts, without departing from the spirit and scope of my invention, as defined in the appended claims.

In the drawings the numeral 2 designates the supporting pedestals which are spaced at proper intervals within the trench in which the conduit is placed. After the pedestals have been formed the lower half of the terra cotta casings 3 is placed in position in the usual manner. After these sections of the casing have been properly placed, the conveyer pipe 4 is placed in position; and connected to the conveyer pipe about centrally above each of the pedestals 2 is a supporting bracket 5. This supporting bracket comprises a body portion and down-

wardly extending lugs 6 at each end thereof. These lugs are forked, and rotatably mounted on pins 7 are rollers 8 which are seated within the forks. The upper face of the body portion of each of these supports is provided with a plurality of lugs 9 which are concaved to fit the pipe 4. Connected to the bottom of the body portion is a metal band or strap 10, which is passed around the top of the pipe, and the ends are connected to each other by means of a bolt 11 to clamp the supports in position on the pipe. After these supports are secured to the pipe at the proper points, the pipe will be supported directly from the terra cotta casing 3, which is in turn supported on the pedestals 2. After the pipe has been placed in position it is covered between the supports with a heat-insulating lagging of any well known type, while the supports are covered with a composition from which the lagging is made, so that the entire length of the pipe is insulated. After the insulating material has been placed in position the upper sections of the terra cotta casing are placed in position and the trench is filled.

By the use of a support such as I have shown and described, I am able to support the conveyer pipe directly upon the terra cotta casing which is in turn supported on the pedestals.

The advantages of my invention result from the provision of a support for incased pipes or conduits in which the supports and the pipe are entirely surrounded by the terra cotta shell, which will prevent moisture from entering the sealed conduit. Further from the provision of a support which is connected directly to the conveyer pipe in such a manner that the pipe is allowed to expand and contract without coming in contact with the stationary surface, thereby avoiding all danger of chafing the insulating material surrounding the pipe. Further from the provision of means for supporting the pipe directly on the terra cotta shell so that the conveyer pipe will always assume its proper position when placed in the casing.

I claim:

1. A pipe support having a concaved seating surface for the pipe, a plurality of rollers connected to said support, a flexible clamping strap surrounding the body portion of the pipe support, and a clamping

screw connected to the ends of the strap; substantially as described.

2. A pipe-supporting bracket having a seating surface for the pipe, a plurality of rollers connected to said bracket, and a flexible strap for clamping the bracket to a pipe; substantially as described.

3. A conduit having a plurality of supports connected directly thereto, a cylindrical casing surrounding the conduit, heat-insulating material surrounding the conduit, there being a space between the heat-insulat-

ing material and the casing, projections on said supports extending through the heat-insulating material, and supporting rollers 15 connected to said projections engaging the inner wall of the casing, substantially as described.

In testimony whereof, I have hereunto set my hand.

PAUL W. LAMSON.
